(57) **CLAIM**

The ornamental design for a takeout clamshell container as shown and described.

DESCRIPTION

FIG. 1 is a perspective view of a takeout clamshell container showing my new design;

FIG. 2 is a perspective view of the takeout clamshell container where the takeout clamshell container is in a opened state;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof, and

FIG. 8 is a bottom plan view thereof.

FIG. 9 is an enlarged view of portion 9 shown in FIG. 1; and, FIG. 10 is an enlarged view of portion 10 shown in FIG. 8. The broken lines in the drawings depict portions of the takeout clamshell container that form no part of the claimed design. The dot-dash broken lines shown represent the designation of enlargement views and form no part thereof.

1 Claim, 10 Drawing Sheets
